US0D1060061S

(12) **United States Design Patent** (10) Patent No.: **US D1,060,061 S**
(45) Date of Patent: ** Feb. 4, 2025

(54) **FOOD THERMOMETER**

(71) Applicant: **FINEMOLD TECHNOLOGIES CO., LTD**, Shenzhen (CN)
(72) Inventor: **Peng Lu**, Shenzhen (CN)
(73) Assignee: **FINEMOLD TECHNOLOGIES CO., LTD**, Shenzhen (CN)

(**) Term: **15 Years**

(21) Appl. No.: **29/959,851**

(22) Filed: **Aug. 28, 2024**

(51) LOC (15) Cl. **10-04**
(52) U.S. Cl.
USPC **D10/57**

(58) **Field of Classification Search**

USPC D10/57, 60
CPC G01K 2207/06; G01K 2207/02
See application file for complete search history.
